LIFTING CLAMP

Stanley Robson, Parktown, Johannesburg,
Transvaal, Union of South Africa

Application December 1, 1949, Serial No. 130,405
In the Union of South Africa November 24, 1949

1 Claim. (Cl. 294—106)

1

This invention relates to lifting clamps to enable plates of steel or other materials to be lifted.

The object of the invention is to provide an automatically operated lifting clamp which, under load, will retain its grip at any angular position between the horizontal and the vertical.

According to this invention there is provided a lifting clamp comprising a pair of internally cam surfaced clamping jaws, pivots for the lower parts of the jaws connected by an inwardly arched bridging member, and a pair of pantographic links rotatably connected together at their upper ends and each pivotally connected at their lower end to the upper part of each corresponding jaw. Stops are provided limiting the outward movement of the jaws.

The invention is illustrated in one preferred form in the accompanying drawings in which:

Fig. I is a side elevation of the clamp;

Fig. II is a similar view to Fig. I showing the clamp in its horizontal lifting position;

Fig. III is a side elevation of the clamp in its vertical lifting position; and

Fig. IV is a side elevational view, showing the clamp in the position illustrated in Fig. III.

As shown in the drawings there is provided a pair of clamping jaws 1, 2, which are pivoted near their ends 3, 4 on pins 5, 6. The jaws 1, 2 are internally cam shaped, that is, they are made to protrude towards one another. The pins 5, 6 are connected by means of an arched shaped bridging member which conveniently takes the form of the frame 7. The frame 7 consists of a pair of opposite plates 8 rigidly held parallel to each other by the ties 9. The bottoms 10 of the plates 8 have inwardly extending gaps or recesses 11 to enable a plate to be inserted between the jaws 1, 2.

The jaws 1, 2, are positioned between the parallel plates 8 and are provided with suitably hardened and serrated clamping faces 12, 13 of cam shape.

Pins 14, 15 are fitted through the upper portions 16, 17 of the jaws 1, 2 and project through arcuate slots 18, 19 in the plates 8, which act as stops to limit the movement of the pins 14, 15 and thus the jaws 1, 2.

On the outer ends of the pins 14, 15 are rotatably fitted a pair of pantographic links 20, 21 which in turn are connected at their upper ends by pin 22. Pin 22 carries a U shaped lifting shackle 23 into which the hook 24 of a crane or other lifting device may be passed.

For use the frame 8 is positioned on its side and the edge of the plate 25 to be lifted is inserted between the jaws 1, 2 as shown in Fig. I. In this position the pin 14 rests on the outer end of slot 18 and plate 25 rests on the face 12 of jaw

2

1 which latter projects a small amount across recess 11 and the face 13 of jaw 2 rests on plate 25. As the shackle 23 and links 20, 21 are raised to lift the load the pins 14, 15 swing inwardly until pin 15 bears against the end of slot 19 thus limiting any further inward movement of jaw 2 relative to frame 8 as shown in Fig. II. In this position the inward movement of pin 14 is limited by jaw 1 bearing against the bottom of plate 25 which is thus gripped between jaws 1 and 2. If the plate 25 is gripped by two or more clamps at opposite edges this will be the normal position of the lifting clamps.

If, however, the plate 25 is lifted by a single clamp, as said plate is swung from the horizontal to the vertical position, the jaws 1, 2 will swing from the positions shown in Figs. I or II to centralise themselves across the recess 11 as shown in Fig. III. It will be seen that the pantographic action of links 20, 21 and jaws 1, 2 will cause the faces 12, 13 of the latter to grip the plate 25 in all positions between the horizontal and vertical.

The clamping action will be increased as plate 25 approaches the vertical position. This is due to the position of pins 5, 6 relative to the clamping faces 12, 13 which result in the latter having a wedge-like action as the downward pull of the weight of plate 25 becomes effective.

This invention thus provides a lifting clamp of simple construction which acts efficiently to grip a plate, or the like, in all normal positions.

What I claim as new and desire to secure by Letters Patent is:

A lifting clamp consisting of a pair of plates 35 rigidly held in parallel spaced relation, corresponding centrally positioned inwardly arched recesses, one in the bottom of each plate, a pair of clamping jaws, serrated cam shaped clamping faces for the jaws projecting across said recesses, a pair of pivots in the clamp one positioned 40 on each side of the recess for holding the outer ends of the jaws, a pair of arcuate slots in each plate, pins fitting through the upper portions of the jaws and projecting through said arcuate slots, a pair of pantographic links rotatably connected at their inner ends to the pins and a shackle rotatably connected to the outer ends of said links.

STANLEY ROBSON.
